UNITED STATES PATENT OFFICE.

JACOB RUPPERT, OF BETHELEHEM, PENNSYLVANIA.

SAW CLAMP.

1,410,512.

Specification of Letters Patent. Patented Mar. 21, 1922.

Application filed October 28, 1919. Serial No. 333,880.

To all whom it may concern:

Be it known that JACOB RUPPERT, a citizen of the United States of America, residing at Bethlehem, in the county of Lehigh and State of Pennsylvania, has invented new and useful Improvements in Saw Clamps, of which the following is a specification.

The object of the invention is to provide a simple and inexpensive saw holding clamp for supporting a saw blade in proper position for filing or setting and designed to be readily supported upon a bench or suitable convenient object, and to this end the invention consists in a construction and combination of parts hereinafter described, it being understood that changes in form and proportion may be resorted to within the scope of the claims without departing from the principles involved.

In the drawings:

Figure 1 is a perspective view of the clamp.

Figure 2 is a detail view of the mounting by which the adjustable arms are connected.

Figure 3 is a sectional view of said mounting.

The blade-engaging heads 10 and 11 are disposed and held in parallelism by arms 12 and 13 to which the bars constituting the heads are pivotally connected as at 14 so as to adapt them to assume any angular position which may be convenient to the operator, and said arms are pivotally connected at an intermediate point by a mounting 15 and are adapted to be angularly moved to dispose the heads in clamping relation with an interposed saw blade by means of an adjusting screw 16 preferably having a thumb piece 17 or the equivalent thereof. The connection between the head-supporting arms preferably consists of a bracket 18 secured for example to the arm 12 and having

extensions 19 between which the arm 13 operates, and a plate 20 secured to the arm 13 and having a knuckle 21 through which extends a pivot bolt 22 engaged with the extensions 19.

Also the head 10 is preferably provided with terminal hooks 23 for engagement with a bench or other means of supporting the tool.

It will be obvious that upon disposing the blade of a saw between the facing surfaces of the head elements 10 and 11 and moving the same to any convenient angular relation with the arms by which they are supported, the adjusting means may be operated to clamp the blade in place, and that any subsequent adjustment of the head elements to suit the convenience of the operator in the course of filing the saw teeth may be effected without detracting from the efficiency of the engagement of the head elements of which the outer edges may be disposed close to the line of the saw teeth.

What is claimed is:

A device for the purpose indicated comprising a pair of blade engaging sleeves provided with depending arms, and means for pivotally connecting the arms, the said means comprising a bracket secured to one of the arms and having parallel spaced extensions which at one end overlap the edges of the arm to which the bracket is attached and extend into overlapping relation with the corresponding edges of the other arm, a plate secured to the inner face of the said other arm and provided with a transversely disposed knuckle, and a pivot bolt extending through the knuckle and through the said extensions.

In testimony whereof he affixes his signature.

JACOB RUPPERT.
